UNITED STATES PATENT OFFICE.

WILLIAM F. KIEFER, OF PHILADELPHIA, AND JOHN HENRY WARREN, OF JENKINTOWN, PENNSYLVANIA.

CONVERTIBLE BUILDER'S LEVEL AND TRANSIT.

Application filed January 14, 1922. Serial No. 529,126.

To all whom it may concern:

Be it known that we, WILLIAM F. KIEFER, a citizen of the United States, residing at Philadelphia, county of Philadelphia, State 5 of Pennsylvania, and JOHN HENRY WARREN, a citizen of the United States, residing at Jenkintown, county of Montgomery, State of Pennsylvania, have invented a new and useful Convertible Builder's Level and 10 Transit, of which the following is a specification.

Our present invention relates to a novel construction and arrangement of a convertible builder's level and transit and comprehends more particularly a novel construction forming a permanent part of the 15 level for enabling the telescope to be supported at right angles to its normal position in trunnions or axles thus enabling the telescope to be elevated or depressed through an angle of at least 45° above and below the horizontal.

It further comprehends a novel construction of telescope supports wherein novel 20 means are employed for closing them and novel means are employed for effecting their rotary adjustment.

Other novel features of construction and advantage will hereinafter more clearly appear 25 in the detailed description of the invention.

For the purpose of illustrating our invention, we have shown in the accompanying drawing a typical embodiment thereof which is at present preferred by us, since this embodiment will be found in practice to give 30 satisfactory and reliable results. It is, however, to be understood that the various instrumentalities of which our invention consists can be variously arranged and organized and that our invention is not limited to the precise arrangement and organization 35 of these instrumentalities as herein shown and described.

Figure 1 represents, in side elevation, a convertible builder's level and transit, embodying our invention.

Figure 2 represents, in side elevation, the construction seen in Figure 1 but showing 50 certain of the parts in a different position from that shown in said figure.

Figure 3 represents a section on line 3—3 of Figure 8.

Figure 4 represents a side elevation of the 55 construction seen in Figure 3.

Figure 5 represents a top plan view.

Figure 6 represents a section on line 6—6 of Figure 5.

Figure 7 represents a section on line 7—7 of Figure 2.

Figure 8 represents a top plan view similar to Figure 5 but showing the telescope and its adjuncts at right angles to the position seen in Figure 5.

Figure 9 represents a section on line 9—9 of Figure 6.

Figure 10 represents a section on line 10—10 of Figure 7.

Similar numerals of reference indicate corresponding parts.

Referring to the drawings.

1 designates the Y support which is preferably in the form of a bar provided with any conventional type of means for effecting its vertical horizontal and lateral adjustment. The Y support 1 carries the Y's 2 which are provided with a threaded rod 3 which passes through the Y support 1 and is in engagement therewith and secured in adjusted position by means of the lock nuts 4. The screw or threaded rod 3 is cut away on opposite sides of its center to form the parallel walls 5 against which are adapted to bear the adjusting screws 6 and 7, respectively, which are in threaded engagement with the Y support. This provides for an accurate rotary adjustment and alignment of the Y's with respect to their support. The Y's as is customary are provided with an upper curved arm 8 which is pivoted at 9 with the body portion of the Y and the free end of this arm 8 engages a recess or slot 10 in the body portion of the Y when in closed position. The free end of the arm 8 is provided with the vertically disposed threaded aperture 11 adapted to receive the threaded end 12 of a locking member 13 which is provided with the bearing portion 14 mounted to revolve in the aperture 15 in the body portion of the Y. This aperture 15 does not extend through the Y but forms a shoulder against which the bearing portion of the shoulder abuts. In order to prevent longitudinal movement of the locking member 13 with respect to the body portion of the Y, the bearing portion 14 is provided with a groove 16 into which extends a screw 17, see more particularly Figures 6 and 9.

The Y's carry the telescope 18 which is provided in the usual manner with a level 110

19. The telescope 18 is provided with the trunnions 20. The Y support carries as a permanent part of it a telescope supporting mechanism which supports the telescope in a novel manner when this telescope is to be moved in a vertical plane for sighting points above or below the horizontal.

21 designates supplemental telescope supporting members which are formed of casting or sheet metal and are provided at their lower ends with the extensions or ears 22 which are pivotally connected with opposite sides of the Y support by means of the screws 23. Intermediate the extensions 22 the body 10 portion of the supporting members 21 are provided with the L-shaped leg 25 which with the screws 23 forms a three point support for each telescope supporting member 21.

20. Each telescope member at its outer end is recessed as at 26 having a V-shaped bottom and parallel side walls to receive and form the bearings of the trunnions 20 of the telescope. The depth of each recess 26 is such 25 that the periphery of a trunnion 20 co-operating therewith extends above the free end of a telescope supporting member 21.

27 designates a spring plate secured to the outer end of a telescope supporting member 21 by means of fastening devices 28.

In order to lock the telescope supporting members 21 in their raised position, we provide a manually actuated locking member 29 which is rotatably mounted on the Y support 1 by means of a fastening device 30. This locking member 29 is provided with the diametrically located slots 31 through which the legs 25 are adapted to pass when the members 21 are raised. When 40 the locking member 29 is moved from the position seen in Figure 5 to that seen in Figure 8, it will be apparent that it will overhang the lateral flange 32 of each leg and thereby lock the members 21 in their 45 raised position. A spring washer 33, see Figure 8, is preferably employed beneath the head of the fastening device 30.

The operation will now be readily apparent to those skilled in this art and is as 50 follows:—

Referring first to Figures 7 and 10, it will be apparent that the Y's can be rotatably adjusted in their supports and locked in adjusted position by means of the adjusting screws 6 and 7.

In order to retain the telescope 18 and lock it in position in the Y's, the telescope is placed on the body portion of the Y's and the arm 8 of each Y swung into closed position. 60 The locking member 13 is then rotated whereupon the threaded portion of shank 12 will engage the threaded aperture 11 and cause an arm 8 to be drawn into its closed position and locked in such position. Since 65 the direction in which the closing move-

ment of the arm of each Y is caused by pressure exerted in a vertical direction, there is no likelihood of the co-operating parts of the Y being drawn out of alignment.

If it is desired to mount the telescope in the trunnions in order to sight points above or below the horizontal, all that it is necessary to do is to unscrew the locking members 13, raise the arms 8, remove the telescope, raise the members 21 from the position seen in Figures 1 and 5 into substantially the position seen in Figures 2 and 8, insert the trunnions 20 of the telescope into the recesses 26 and then rotate the locking member 29 from the position seen in Figure 8 into that seen in Figures 2 and 8, whereupon the telescope will assume a position at right angles to its former position when supported in the Y's and be capable of movement in the vertical plane. 85

Special attention is directed to the three point support of each supporting member 21 when in raised position, the three points being the fastening devices 23 and a supporting leg 25. It will be apparent from Figure 8 that the point at which the pressure is exerted by the locking member 29 on each support 21 is disposed within a triangle formed by the three supporting points 23 and 25. This three point support compensates for wear so that the telescope supporting member 21 will always assume the proper position when raised. 95

In accordance with our invention, we provide a novel construction of a support for this purpose which forms a permanent part of the instrument, the advantages of which are self evident. 100

It will be apparent that the spring plate 27 is tensioned against the trunnions of the telescope so that the telescope will be retained in any position of elevation or depression in the vertical plane desired. 105

It will be apparent that in accordance with our invention, the instrument can be converted for vertical sighting without the use of detachable parts, and when the telescope is supported in the Y's no obstructions are present to obscure a full view of the level vial. A range of inclination of at least 45° 110 above or below the horizontal is obtained. The locking member 29 with the spring washer 33 which is preferably connected with it, serves as a spring tension locking device to securely and accurately hold each member 21 in its upright position. The trunnions of the telescope are preferably of small diameter and are permanently attached at or near the center of gravity of the telescope. 115

Attention is directed to the fact that the supporting members 21 which are pivotally connected at their lower ends with the Y support or level bar 1 but remaining fixtures of the latter, may be folded down on said 120 125 130

bar and so when they are not in use for supporting the telescope (when the devices is adapted to render service as a transit), they will not obscure the spirit level nor obstruct 5 the view of the bubble thereof, as most apparent in Figure 1.

Again, when the members 21 are folded as above stated, they will not interfere with the mounting of the telescope in its normal 10 position upon the Y's when used as a level as shown in Figure 1.

It will now be apparent that we have devised a novel and useful convertible builder's level and transit which embodies the 15 features of advantage enumerated as desirable in the statement of the invention, and the above description, and while we have, in the present instance, shown and described an embodiment thereof which will 20 give in practice satisfactory and reliable results, it is to be understood that this embodiment is susceptible of modification in various particulars without departing from the spirit or scope of the invention or sacrificing any of its advantages.

Having thus described our invention, what we claim as new and desire to secure by Letters Patent, is:

1. In a device of the character described, 30 the combination with the telescope, the Y's to carry it and the Y support, of telescope supporting members permanently carried by said Y support and having means to support said telescope in one position and supplemental means pivotally mounted on said 35 Y's support and foldable thereon and adapted when raised to form the bearings of the trunnions of the telescope at a right angle to said position, and means to lock said 40 members in operative position.

2. In a device of the character described, 45 the combination of a telescope and Y's support, on which latter said telescope is mounted in one position of supplemental supporting members for the telescope pivotally mounted on said support and foldable thereon and adapted when raised to form the bearings of the trunnions of the telescope at a right angle to said position, said 50 supplemental members having thereon resilient elements adapted to correspondingly engage said trunnions.

3. In a device of the character described, 55 the combination with the telescope, the Y's to carry it and the Y support, of telescope supporting members carried by and having a three point bearing on said Y support and having means to support said telescope so that it can be elevated or depressed in the 60 vertical plane at least 45° above and below the horizontal, and means to lock said members in operative position.

4. In a device of the character described, 65 the combination with the Y support, of a Y having a threaded rod in engagement with

said support, a portion of said rod being removed on opposite sides to form bearing faces and laterally adjustable members carried by said Y support to engage said bearing faces to effect the rotary adjustment of 70 said Y with respect to its support.

5. In a device of the character described, 75 a Y having a body portion, a movable arm pivotally connected to one end of said body portion, a vertically disposed locking member rotatable but prevented from longitudinal movement with respect to said body portion and having a threaded stem to engage the free end of said arm and lock it in closed position.

6. In a device of the character described, 80 the combination with a Y support, the Y's carried thereby and the telescope supported on said Y's, of telescope supporting members carried foldably by said Y support and having a three point bearing when in raised position to support said telescope, and means exerting a locking pressure against said telescope supporting members to retain them in raised position, said pressure being exerted within a triangle defined by the three points indicative of the three point bearing.

7. In a device of the character described, 85 the combination with a Y support, the Y's, the telescope adapted to be carried by the Y's, of telescope supporting members, each pivotally connected with said Y support at two points and having means engaging said Y support when such members are in raised position to form a three point bearing, and 90 a locking member to retain said members in raised position.

8. In a device of the character described, 95 the combination with a Y support, the Y's carried by it and the telescope supported in said Y's, of a pair of telescope supporting members pivotally connected at two points to said Y support and having a leg to engage said Y support when said members are in raised position, a locking member rotatably 100 mounted on said Y support and adapted to overhang said legs to secure said supporting members in raised position, and means for mounting a telescope with respect to said members so that it can be elevated or 105 depressed in the vertical plane at least 45° above or below the horizontal.

9. In a device of the character described, 110 the combination with the Y support, the Y's and the telescope, of supplemental telescope 115 supporting members pivotally mounted on said Y's and having recesses in their outer ends to receive the trunnions of the telescope, and a tension device on each member to resiliently retain a trunnion in its recess, whereby 120 the telescope when assembled with said members will be retained in any position of elevation or depression in the vertical plane 125 desired.

10. In a device of the character described, 130

the combination with a Y support, the Y's and the telescope, of telescope supporting members pivotally connected at two points to said support in proximity to its center 5 and each having a recess to receive a telescope trunnion, said members each having a leg to engage said support when in raised position, a locking member rotatably mounted having slots through which said legs 10 pass when being raised, and having portions to overhang said legs to secure said members in raised position, and a tension device for said locking member.

11. In an instrument of the character 15 stated, a telescope, a bar having means there-

on adapted to removably support the telescope thereon in longitudinal direction and supplemental members pivotally mounted on said bar said supplemental members having thereon means to form the bearings of the 20 telescope in transverse direction when used as a transit, said supplemental members being adapted to be folded down on said bar when the telescope is to be used as a level.
